UNITED STATES PATENT OFFICE.

JAMES C. STUBBS, OF MOUNT PLEASANT, IOWA.

WHEELED SCRAPER.

SPECIFICATION forming part of Letters Patent No. 703,098, dated June 24, 1902.

Application filed February 4, 1902. Serial No. 92,528. (No model.)

To all whom it may concern:

Be it known that I, JAMES C. STUBBS, a citizen of the United States, residing at Mount Pleasant, in the county of Henry and State of Iowa, have invented certain new and useful Improvements in Wheeled Scrapers, of which the following is a specification.

My invention relates to that class of earth excavating and transferring devices known as "scrapers," my improvements being applicable more particularly to that type of scraper in which the pan is suspended from an axle supported by a pair of carrying-wheels, the pan being lowered to cutting and scooping position and subsequently raised to carrying position and tilted to effect the dump by means of a rearwardly-extending lever actuated by the operator. A fault hitherto inherent in devices of this type has resided in the severe burden imposed upon the operator and team in the act of breaking out of the ground the cutting edge of the scraper-pan after it has received its load and when broken out of the ground elevating the pan to its latching and carrying position. Most of these scrapers now in use have their draft-irons pivoted to the pan or to the axle, while the pan itself is suspended from the forward forked end of a rearwardly-extending operating-lever, termed the "Johnson bar," fulcrumed on the axle. With this construction the entire onus of lifting the loaded pan from loading to carrying position is imposed on the operator, who accomplishes it by a downward pull on the Johnson bar. Owing to the firmness with which the pan after taking its load is often embedded in the earth from which the excavations are being made, this elevation of the pan clear of the ground through the surrounding and superincumbent earth to carrying position is, especially in the case of scrapers of large capacity, a severe strength-taxing operation, often requiring the united efforts of two men.

My invention has for its object to obviate the fault hereinabove referred to by such a construction and connection of the draft-irons to the axle as shall throw the principal onus of this operation upon the team, and that too at such a mechanical advantage as not to seriously add to the exertion and effort required of the latter.

To this end my invention consists in a combination of mechanical devices for effecting the result above stated in a highly efficient manner, substantially as hereinafter described and claimed.

In the accompanying drawings, Figure 1 is a side elevation of my improved scraper, one wheel being removed and the axle shown in transverse section for greater clearness, the full lines illustrating the loading position of the device and the dotted lines illustrating the carrying position; and Fig. 2 is a plan view of the scraper complete.

In the drawings, A designates the pan in the usual form. This pan is pivotally suspended at points slightly forward of its longitudinal center from the forward end of a forked operating-lever commonly known in this art as the "Johnson bar." As shown, this Johnson bar comprises a rearwardly-extending handle B, connected at its inner end to a fork or bail i, the parallel forwardly-extending arms of which are rigidly secured to the offset bends of an arched axle n, the pan being suspended from the forward ends of said forwardly-extending arms by means of hangers A'. For the sake of greater rigidity a brace l connects the forward or inner end of the handle B with the top of the central offset portion of the axle n. Pivoted to and pendent from the inner end of the handle B is the usual hook or latch k, which when the bar is lowered engages a coöperating catch k' on the rear of the pan. A pair of rearwardly-extending handles C, secured to the upper rear corners of the sides of the pan, enable the operator to correctly poise and guide the pan in the loading operation.

The parts as thus far described are old and well known in scrapers of this class. The outer ends of the axle n are journaled in a pair of carrying-wheels D, and those portions of the axle lying between the journals and the bends are conveniently formed of rectangular or other polygonal cross-section, as clearly shown at a, for a purpose that will hereinafter appear.

Referring next to those features which comprise the gist of my present invention, b represents a pair of crank-arms, the inner ends of which are apertured to pass over the journals of the axle and snugly fit the squared

- portions of the latter above referred to. As will be seen by reference to Fig. 1, these crank-arms are positioned at substantially a right angle to the plane of the bends of the axle.
- 5 These crank-arms are of considerable length, the forward ends thereof extending radially to a distance approximating one-third the radius of the carrying-wheels. To the forward ends of these crank-arms are pivotally connected 10 at *c* the inner ends of the draft-irons *d*, the forward ends of which latter are connected to the usual pole *e*. Pivoted to and pendent from the draft-irons at a suitable point thereon are a pair of draft-hooks *f*, the lower ends 15 of which are adapted to engage and disengage companion hooks *h*, fast on the sides of the pan near their lower forward ends. Links *g*, pivoted at one end to the forward ends of the Johnson bar at the pivotal connection of the 20 latter with the hangers *A'* and at their other end to the hooks *f* at intermediate points on the latter, serve to properly actuate said draft-hooks simultaneously with the actuation of the Johnson bar and the raising and lowering 25 of the pan. Pivoted on the rear end of the pole *e* is the usual hooked link *m*, adapted to engage the bail or inner bifurcated portion of the Johnson bar when the latter is elevated.
- 30 When a load is to be taken, the handle of the Johnson bar is raised to or beyond the position shown in full lines in Fig. 1, the hook *k* having been released from the rear of the pan. This operation permits the pan 35 to drop, at the same time turning the axle in its bearings in the hubs of the wheels and throwing the arched portion of the axle downwardly and forwardly. This same operation also swings the crank-arms *b* from a substantially horizontal position to the downwardly-inclined position shown in Fig. 1 and simultaneously forces the draft-hooks *f* into engagement with their companion hooks *h*. The team is then started up and the load 40 taken on, the draft being applied at the pivots *c* and the hooks *h*. The pan having been filled, the handle of the Johnson bar is pulled down, which operation raises the forward or cutting edge of the pan, while the bottom of 45 the pan at its rear end still rests upon the ground. The raising of the forward portion of the pan elevates the hangers *A'*, in the upper ends of which the rear ends of the links *g* are pivoted, which movement, through the 50 links *g*, retracts the lower ends of the draft-hooks *f* sufficiently to disengage the latter from the pan-hooks *h*. The draft of the team being at the same time applied at the pivotal points *c* on the extremities of the crank-arms 55 60 *b* the latter are pulled forward and upward into longitudinal alinement with the draft-irons. This produces a partial backward rotation of the axle in the hubs of the carrying-wheels, which co-operates with the effort of 65 the operator exerted on the Johnson bar in raising the pan clear of the ground to the extent of relieving the operator of the bulk

of this labor. At the same time this initial forward movement of the draft-irons relatively to the axle and pan advances the upper ends of the draft-hooks *f* and so changes their pitch or inclination to the sides of the pan sufficiently to carry the lower ends of hooks *f* behind and fully clear of the hooks *h*, all as clearly illustrated by the dotted-line 70 position of the parts shown in Fig. 1. The load having been carried to its destination is dumped in the manner usual to this class of scrapers, and on returning to the place of excavation the parts are again caused to assume 80 the loading position by releasing the hook *k* and elevating the handle of the Johnson bar, which operation throws down the crank-arms *b* to an angle with the draft-irons and at the same time effects the automatic reengagement 85 of the draft-hooks *f* with the pan-hooks *h*. The above-described cycle of operations is then repeated.

It will be evident that the hereinabove-described and illustrated embodiment of my 90 invention might be varied and modified to some extent without departing from the principle and spirit thereof. I do not, therefore, limit myself to the exact details shown and described, except to the extent that they may 95 be made the subject of specific claims.

I claim—

1. In a scraper of the class described, the combination with the axle and its carrying-wheels, the Johnson bar fulcrumed on the 100 axle, and the pan suspended from the overhanging end of the Johnson bar, of draft-irons united to the axle by a jointed connection which, on the application of the draft, tends to partially rotate the axle backwardly 105 in the wheels and thus elevate the pan, substantially as described.

2. In a scraper of the class described, the combination with the arched axle and its carrying-wheels, the Johnson bar fulcrumed on 110 the bends of the axle, and the pan suspended from the overhanging end of the Johnson bar, of rigid projections on and extending forwardly of the axle substantially at a right angle to the bends of the axle, and draft-irons 115 pivoted to the forward ends of said projections, substantially as and for the purpose described.

3. In a scraper of the class described, the combination with the arched axle and its carrying-wheels, the Johnson bar fulcrumed on 120 the bends of the axle, and the pan suspended from the overhanging end of the Johnson bar, of a pair of forwardly-projecting crank-arms keyed fast on the axle between the journals 125 and the bends of the axle, respectively, and disposed at substantially a right angle to the bends of the axle, and a pair of draft-irons pivoted at their inner ends to the forward ends of said crank-arms, substantially as and 130 for the purpose described.

4. In a scraper of the class described, the combination with the arched axle and its carrying-wheels, the Johnson bar fulcrumed on

the bends of the axle, and the pan suspended from the overhanging end of the Johnson bar, of a pair of crank-arms rigidly mounted on squared portions of the axle lying between 5 the journals and the bends thereof, respectively, and projecting forwardly substantially into the transverse plane of the points of suspension of the pan from the Johnson bar, and a pair of draft-irons pivoted at their inner 10 ends to the forward ends of said crank-arms, the parts being so disposed that the application of the draft carries the crank-arms from an angular position relatively to the draft-irons into longitudinal alinement 15 therewith, at the same time turning backward the axle in its bearings and elevating the pan.

5. In a scraper of the class described, the combination with the arched axle and its carrying-wheels, the Johnson bar fulcrumed on 20 the bends of the axle, and the pan suspended from the overhanging end of the Johnson bar, of a pair of crank-arms keyed fast on the axle between the journals and the bends thereof, respectively, and extending forwardly substantially parallel and coextensive with the overhanging end of the Johnson bar, a pair 25 of draft-irons pivoted at their inner ends to the forward ends of said crank-arms, a pair of draft-hooks pivoted to and depending from

said draft-irons, coöperating catch-hooks on 30 the pan, and means whereby said draft-hooks are automatically actuated by the movements of the Johnson bar and draft-irons, substantially as described.

6. In a scraper of the class described, the 35 combination with the arched axle and its carrying-wheels, the Johnson bar fulcrumed on the bends of the axle, and the pan suspended from the overhanging end of the Johnson bar, of a pair of crank-arms keyed fast on the axle 40 between the journals and the bends thereof, respectively, and extending forwardly substantially parallel and coextensive with the overhanging end of the Johnson bar, a pair 45 of draft-irons pivoted at their inner ends to the forward ends of said crank-arms, a pair of draft-hooks pivoted to and depending from said draft-irons, coöperating catch-hooks on the pan, and actuating-links for said draft-hooks pivoted at their inner ends to the forward end of the Johnson bar and at their outer ends to the draft-hooks, substantially as described. 50
